UNITED STATES PATENT OFFICE.

ROMUALD J. KARASINSKI, OF PHILADELPHIA, PENNSYLVANIA.

WASHING AND DRYING MACHINE.

Application filed December 28, 1923. Serial No. 683,247.

To all whom it may concern:

Be it known that I, ROMUALD J. KARASINSKI, a citizen of the United States, residing at Philadelphia, county of Philadelphia, State of Pennsylvania, have invented a new and useful Washing and Drying Machine, of which the following is a specification.

My present invention comprehends a novel construction and arrangement of a combined washing and drying machine, wherein the washing, rinsing, bluing and drying are accomplished by centrifugal action created by a novel distributor and basket revolving at a desired speed, without rendering it necessary to remove the clothes from the machine.

It further comprehends a novel construction and arrangement of driving mechanism to effect the revolution of the basket and distributor and also of liquid feeding means.

It further comprehends a novel construction and arrangement of a wash containing basket, novel means for mounting it, and a novel construction and arrangement of a distributor, disposed within the basket and revolving in unison therewith.

It further comprehends a novel construction and arrangement of shock absorbing means.

Other novel features of construction and advantages will hereinafter more clearly appear in the detailed description and the appended claims.

For the purpose of illustrating the invention, I have shown the accompanying drawing of a typical embodiment of it, which, in practice, will give reliable and satisfactory results. It is however to be understood that this embodiment is typical only, and that the various instrumentalities of which my invention consists can be variously arranged and organized, and that the invention is not limited to the precise arrangement and organization of these instrumentalities as herein set forth.

Figure 1 represents, in sectional elevation, a washing and drying machine embodying my invention.

Figure 2 represents a section on line 2—2 of Figure 1.

Figure 3 represents a perspective view of a ball container and its balls, in detached position.

Similar numerals of reference indicate corresponding parts.

Referring to the drawings:

1 designates a washing and drying machine embodying my invention. The machine is provided with a desired number of supporting standards or legs 2 which at their lower ends are flanged and connected in any desired manner to a bottom plate 3 which preferably is in the form of a spider. This bottom plate 3 is provided with apertures 4 preferably disposed beneath the flanges of the standards 2, and these apertures form sockets to receive the shanks of elastic or resilient cushions 5 which are preferably made of rubber and are recessed at the bottom, as indicated at 6. These cushions 5 rest on the depressed top portions 7 of slides 8 which are preferably formed from sheet metal, and are provided at their bottoms with an annular flange 9, to the bottom of which is connected in any desired manner a ring 10 of leather, fibre or any other desired material which will prevent injury to the floor on which the washing machine is placed.

The standards 2 at their upper ends are flanged to form a support for a plate 11, which is secured thereto by means of fastening devices 12. The central portion of the plate 11 is deflected downwardly as indicated at 13, and at its lower portion, it has a bushing 14 secured within it. 15 designates a container to receive the cleansing liquid, and the bottom 15' of this container is supported on the plate 11 and secured thereto by means of the fastening devices 12. 16 designates an inner housing, which is flanged at its bottom in order to receive fastening devices 17 which pass through the plate 11, and through the bottom 15' of the container 15. The housing 16, intermediate its top and bottom, is provided with an inwardly directed flange 18, to which is connected the flange of a sleeve 19 by means of fastening devices 20 in such a manner as to form a water tight joint. At the upper end portion of the inner housing 16, a bushing 21 is provided to receive the lower end of a sleeve 22, the upper end of which is provided with an outwardly extending flange which is secured to the bottom of the wash containing basket 23 by means of fastening devices 24. The cleansing fluid is indicated at 25, and is raised by means of a pump 26 of any desired or conventional type, which raises the cleansing fluid through the discharge con-

100
105
110

duit 27, which preferably flares at its discharge end and discharges into the chamber 28 from whence it rises through the passage 29 into the distributor 30. This distributor 30 is preferably formed from sheet metal and has an imperforate top and bottom. The bottom is centrally cut away and is secured by means of fastening devices 24 to the bottom of the wash containing basket 23 and also to a spider 31. The spider 31 is keyed or otherwise connected with the upper end of a shaft 32, so that it will revolve in unison therewith, but can with the basket be lifted off when desired. The distributor 30 is provided with perforations 33 in its side wall, so that the water will impinge against the clothes or wash 34 disposed within the basket 23, and, after it passes through the wash, it passes through the perforations 35 in the outer wall of the basket 23, as clearly illustrated in the drawing. The bottom of the wash containing basket 23 is substantially flat at its peripheral portion as at 36, and it then merges into an upwardly deflected central portion 37. The side wall of the basket 23 is preferably deflected inwardly at its upper portion as at 38. The container 15 is provided with a removable cover 39. The shaft 32, which effects the revolution of the distributor 30 and the wash containing basket 23, is supported at its lower end by a step bearing 40 carried by the bottom plate 3, and it preferably rests on a single ball 41. If desired, the lower end of the shaft 32 may be recessed to receive a portion of the ball 41.

The driving mechanism.

42 designates a motor of any desired or conventional type, and preferably an electric motor which is carried by the bottom plate 3. The shaft of the motor 42 has connected with it a friction wheel 43. 44 A friction disc 44 is keyed to the shaft 32 so that it is capable of relative longitudinal movement with respect to such shaft. 45 designates a spring the lower end of which abuts against a sleeve 46, the downward movement of which is prevented by means of a pin 47. The upper end of the spring 45 bears against a centrifugally controlled friction member 48, in the form of a disc having the radial channels 49 which receive the balls 50 which are in frictional engagement with the bottom face of the friction disc 44. The outer peripheral portion of the member 48 is upwardly deflected as at 51, and its downward movement is limited by a stop ring 52 secured to the friction disc 44. The friction wheel 43 is also in frictional engagement with a friction disc 53 which is fixed to a pump shaft 54. 55 designates a spring, one end of which bears against the friction disc 53, and its

upper ends bear against a sleeve 56, the upward movement of which is limited by a bearing bushing 57. The friction disc 53 is grooved to receive the forked end of the lever 58 fulcrumed at 59. This lever 59 has connected to it an operating rod or bar 60 which is provided with a grasping portion and with a headed lug 61, which latter is adapted to engage with a strap 62, carried by the casing or container 15. The container 15 is provided with a discharge port 63 which is controlled by a valve 64, to which is connected an operating rod 65 which is slidably between the inner wall of the container 15 and the guides 66 within the container.

The operation of my novel combined washing and drying machine will now be apparent to those skilled in this art and as follows:

I will first describe the washing operation. The wash is placed within the wash containing basket 23, and is substantially uniformly distributed within the basket in proximity to the side walls as shown in Figure 1. Assuming now that the clothes to be washed are in the basket, the motor 42 is started, whereupon the friction discs 44 and 53 will be driven, as is apparent. The spring 45 has only sufficient pressure to retain the friction disc 44 in frictional engagement with the driving friction wheel 43, so that a certain amount of slippage can take place when the machine starts. The friction disc 44 is keyed to the shaft 32, and, as the speed of the shaft increases, the balls 50 due to centrifugal action will travel outwardly thereby increasing the pressure of the spring 45 and the frictional engagement of the disc 44 with the wheel 43. As the shaft 32 is connected to the wash basket 23 by means of the spider 31, and as the distributor 30 is also connected to the spider 31 of the wash basket 23, it will be apparent that the distributor and wash basket will revolve in unison with the revolution of the shaft 32.

The friction wheel 43 is also in frictional engagement with the disc 53 to effect the drive of the shaft 54 and thereby of the pump 26, so that the cleansing liquid will pass through the conduit 27 into the chamber 28 and therefrom through the passage 29 into the chamber of the distributor 30. The cleansing liquid, due to the revolution of distributor 30 and the centrifugal action created, causes the cleansing liquid to pass through the perforations 33 and impinge against and pass through the clothes 34 within the basket 23, thence through the ports 35 in the basket 23, returning to the source of supply 25 within the container 15.

In devices of this character in which the washing action is effected by centrifugal action of the cleansing liquid a large volume

of soap foam is present, and, in order to prevent such soap foam from covering the perforations of the basket 23, the bottom portion 37 of such basket is upwardly deflected in order to provide an enlarged chamber between the level of cleansing liquid in the container 15, and the bottom of the basket. The bottom wall of the basket is preferably imperforate.

10 As soon as the clothes have been properly washed, the operator moves downwardly the rod or bar 60 in order to disengage the friction disc 53 from the driving friction wheel 43, which stops the pump 26. The friction 15 driving wheel 43 is now only driving the friction disc 44, and the drying or extracting of the wash now takes place.

The wash basket is positioned above the permanent level of the cleansing liquid 25, 20 so that the water does not interfere with the revolution of the basket. It is not necessary to drain off the water before the extracting actually takes place, and the same cleansing fluid can be used for a number 25 of different washes, if desired.

If the operator desires to rinse the clothes before extracting without removing them from the basket 23, the cleansing liquid 25 is drawn off, and rinsing water placed in 30 the container 15. The pump is operated to cause the water to pass through the distributor, and from the distributor through the clothes, due to centrifugal action, and the proper rinsing action will be effected.

35 The pump is next disconnected, and the clothes extracted as before explained.

If the clothes are to be blued, they are blued in the bluing water in the same manner as the rinsing operation is effected.

40 It will be apparent from the foregoing that in my present invention I utilize the centrifugal force created by the distributor and basket revolving at a high speed, to wash, rinse, and dry the clothes without removing them from the basket.

Special attention is directed to the novel construction and function of the distributor. This distributor is provided with an enlarged annular chamber, which, due to the 50 centrifugal action created, is effective to reduce the amount of horse power which it is necessary to employ to drive the pump, so that a motor of minimum horse power can be employed.

45 I do not employ the pressure created by the water pump to cause the water to impinge against the clothes. The function of the water pump is to cause the water to be raised, so that, due to the centrifugal action, siphon action and the pump combined, a continuous supply of water will be maintained within the distributor 30. The discharge of the cleansing liquid within the distributor 30 is effected solely by centrifugal 55 action due to the distributor revolving at a

high speed and the diameter of the supply chamber within the distributor. The distributor also serves as a gauge for the placing of the clothes in the basket. The clothes are placed between the side walls of the 70 basket and the distributor so that they will be substantially uniformly arranged within the basket, and abnormal or excessive vibration will be prevented.

Special attention is also directed to the 75 construction employed for eliminating the necessity of employing a packing gland on the shaft 32. This shaft 32 is supported on a bearing formed by the ball 41, and is guided by the bearing 14. There is no likelihood of the cleansing liquid coming into contact with the shaft 32 due to the provision of the sleeve 19 and the cup shaped cap member 67 so that it is not necessary to employ a shaft which is non-oxidizable.

The machine is supported so that it will absorb the shocks due to the vibration. To accomplish this result I employ the resilient or elastic cushions 5 which center themselves in the depressed top faces 7 of 80 the slides 8.

Attention is also directed to the novel means employed to automatically increase the spring pressure on the friction disc 44 as the speed of the shaft 32 increases, so 85 that any excessive load will be taken up gradually enough to reduce the load upon the motor in starting and thus prevents overload of the motor.

The friction losses which have heretofore been present in devices of this character have been materially reduced with a consequent reduction in horse power consumed in driving the motor.

90 The perforated wash basket 23 is supported at the upper end of the shaft 32, and this shaft at its lower end is journaled in an antifriction step bearing. The basket is guided in the inner housing, and the shaft also has a bearing in the plate connected with the bottom of the container. The shaft, so to speak, is floating.

95 The shock absorbing members 5 are free to adjust themselves on the slides 8 when the machine is in operation.

The shaft 32 is supported and guided in such a manner that the necessity of employing a packing gland is eliminated.

100 It will now be apparent that I have devised a new and useful washing and drying machine apparatus which embodies the features of advantage enumerated as desirable in the statement of the invention and the above description, and while I have, in the present instance, shown and described a preferred embodiment thereof which will give in practice satisfactory and reliable results, it is to be understood that this embodiment is susceptible of modification in 105 various particulars without departing from 110

the spirit or scope of the invention or sacrificing any of its advantages.

Having thus described my invention, what I claim as new and desire to secure by Letters Patent, is:

- 5 1. In a washing and drying machine, a container for the cleansing liquid, a basket having a perforated side wall rotatably mounted therein above the level of the liquid, a distributor fixed within said basket to revolve in unison with it and comprising a perforated chambered casing, the chamber of which extends transversely from one side of the casing to the other and is of greater width than depth; means to feed the liquid from said container to said inlet, and means to revolve said basket and distributor.
- 10 2. In a washing and drying machine, a container for the cleansing liquid, a basket having a perforated side wall rotatably mounted therein and having its bottom upwardly deflected to form a soap foam receiving chamber, a distributor comprising a casing carried by said basket and having ports above and below its transverse diameter to cause the liquid to impinge laterally against the entire inner face of the wash, a spider within said casing and connected with said basket, a shaft connected with said spider, means to actuate said shaft, and means to feed the cleansing liquid from said container to said distributor.
- 15 3. In a washing and drying machine, a container for the cleansing liquid, a plate secured to said container, and forming a bearing, an inner housing within said container, a sleeve forming a water tight joint with said inner housing and contributing to form a chamber within said housing, a perforated basket having a sleeve journaled in said housing and contributing with said first sleeve to form a passage communicating with said chamber, a perforated distributor having an enlarged chamber communicating with said passage, a shaft jour-

nalled in said plate bearing and extending through the sleeve connected with said housing and connected with said distributor and basket to revolve in unison therewith, means to feed liquid from said container to said chamber, and means to revolve said shaft.

50 4. In a washing and drying machine, a container for the cleansing liquid, supporting standards, a plate between said standards and container and forming a bearing, a housing within said container, a sleeve forming a water tight joint with said housing and contributing with said housing to form a chamber, a perforated basket having a depending sleeve journaled in said housing and contributing with said first named sleeve to form a passage, a distributor having an enlarged chamber communicating with said passage, a spider connecting said distributor and basket, a shaft extending through said first sleeve and interlocking with the said spider, a step bearing for supporting said shaft, means to feed liquid from said container to said chamber, and means to revolve said shaft.

55 5. In a washing and drying machine, a container for the cleansing liquid, an inner housing within said container and connected to its bottom, a perforated basket journaled in the upper end of said inner housing, a distributor within said basket and carried by it and comprising a perforated chambered casing, the chamber of which extends transversely from one side of the casing to the other and is of greater width than depth, a shaft connected at its upper end to said distributor and basket, standards, a plate thereon supporting said container and having its central portion deflected downwardly to form a shaft bearing, a step bearing for the lower end of said shaft, shaft actuating means, and a pump to feed liquid from said container to said distributor.

60 65 70 75 80 85 ROMUALD J. KARASINSKI.
